UNITED STATES PATENT OFFICE.

HERMAN SACKS, OF CHICAGO, ILLINOIS, ASSIGNOR TO ALBERT T. VAN ALSTYN, OF GRAND RAPIDS, MICHIGAN.

HOSE-SUPPORTER.

1,336,053.

Specification of Letters Patent.

Patented Apr. 6, 1920.

Application filed November 27, 1916. Serial No. 133,746.

To all whom it may concern:

Be it known that I, HERMAN SACKS, a citizen of the United States, residing at Chicago, in the county of Cook and State of Illinois, have invented certain new and useful Improvements in Hose-Supporters, of which the following is a specification.

My invention relates in general to garment supporters, and more particularly to supporters for men's hose.

It is customary to provide supporters for men's hose which may be adjusted to fit different sizes of legs, but in order that they may securely and comfortably support the hose it is necessary that they should vary according to the height of the wearer and the length of the hose. A hose supporter of the proper dimensions for a short man will not be satisfactory for a tall man, nor will a supporter of the proper dimensions for a short hose efficiently support a long hose on the same wearer.

The primary object of my invention is to provide an improved hose supporter which may, without adjustment, be used comfortably and securely to support hose of different length on wearers of various heights.

A further object of my invention is to provide a hose supporter which will be simple in construction, convenient in application, and efficient in use.

My invention will be more fully disclosed hereinafter with reference to the accompanying drawing, in which the same is illustrated as embodied in convenient and practical form, and in which—

Figure 1 is a perspective view of my improved hose supporter in use.

Fig. 2 is a plan view of the same when not in use; and

Fig. 3 is an enlarged sectional view, taken on the line 3—3 of Fig. 2.

The same reference characters are used to designate the same parts in the several figures of the drawing.

My improved hose supporter when in use has the form of a continuous band extending around the leg of the wearer and crossed adjacent its ends, the ends being secured to different portions of the top of the hose, and the crossed portions of the band being pivotally secured together so as to freely rotate

with relation to each other, thereby varying the distance between the portion of the leg which the supporter surrounds and the top of the hose.

The continuous band comprises two detachably connected aligned sections A and B, the ends of the band being provided with suitable fastening devices, C' and C², adapted to detachably engage the top of the hose at spaced points thereon. The fastening devices are preferably mounted upon flexible extensions D' and D², respectively, which underlie the respective fasteners and which are secured to the ends of the band. The fastening devices may be of the usual form, each comprising a loop c' and a button c², between which and the contracted end of the loop a portion of the hose is gripped.

The portions of the sections A and B of the continuous band which cross each other are pivotally connected so as to permit the free relative rotation of such portions, and thereby vary the angle at which they cross. When the hose is long, or the wearer short, the distance between the portion of the leg which is surrounded by the supporter and the top of the hose is less than when the hose is short or the wearer is tall. The pivotal connection between the crossed portions of the supporter permits the fastening devices to be secured to the top of the hose at the desired distance apart without causing the crossed portions to be relatively bent. The hose supporter is therefore permitted to lie flat upon the leg of the wearer, as the crossed portions thereof extend in straight intersecting planes.

Any suitable devices may be provided for pivotally connecting the crossed portions of the supporter, such, for instance, as the well-known glove fastener, comprising a socket member E' secured to the section B, and a button member E² secured to the upper surface of the underlying section A of the supporter. The sections A and B are preferably formed of two plies a' and a², and b' and b², respectively, so that the members of the fastening device may be secured only to the adjacent plies a' and b' of the two sections, as shown in Fig. 3, thereby enabling the members of the fastening device to be entirely concealed when the garter is in use

by the outer ply b^2 of the overlying section B and the inner ply a^2 of the underlying section A.

The continuous band forming the hose 5 supporter comprises a strip of elastic webbing F permanently secured to one end of one of the end sections, such, for instance, as section A. The webbing is folded to form a loop passing through one member H' of the 10 detachable fastening device. G designates a slide mounted upon the elastic webbing, and to which the free end of the webbing is secured for adjusting the length of the band forming the hose supporter in a well-known 15 manner. H² designates the other member of the fastening device, which is secured to the section B adjacent its end opposite to that on which is secured the hose-attaching device C². When the members H' and H² 20 of the fastening device are connected, and the members E' and E² of the device which pivotally connects the crossed sections are detached, the hose supporter has the form of a continuous band.

25 The manner of using my improved hose supporter is as follows: The fastening device C' is secured to the top of the hose at one side of the front thereof, after which the continuous band is passed around the leg of 30 the wearer and the sections A and B crossed, the members E' and E² of the pivotal connecting device being then engaged with each other. The fastening device C² is then secured to the top of the hose at a point adjacent 35 the front thereof, but on the opposite side from the fastening device C'.

When it is desired to remove the hose without detaching the supporter therefrom, the members H' and H² of the fastening device, which connect the adjoining ends of the 40 aligned sections, are disconnected, thereby permitting the removal of the hose with the supporter attached thereto in position again to support the hose when it is placed upon 45 the foot of the wearer.

It will be observed that the various members of the fastening devices all overlie 50 pieces of fabric when the garter is in use, so that none of them comes in contact with the wearer.

From the foregoing description it will be observed that I have invented an improved 55 supporter for men's hose which may be conveniently attached to the hose and placed around the leg of the wearer, and which will efficiently support the hose in use, regardless of the length thereof or the height of the wearer. It will further be observed that the pivotal connection between the cross sections 60 of the supporter permits such sections to lie flat against the leg of the wearer for all adjustable positions of the supporter.

While I have described in more or less detail the specific embodiment of my invention herein illustrated, yet it will be under-

stood that I do not wish to be limited thereto, but contemplate changes in form, proportion of parts, and the substitution of equivalents as occasion may require, or as may be deemed expedient.

I claim:—

1. A hose supporter composed of a continuous band adapted to surround the leg of a wearer with its end portions crossed, two part separable means secured to the crossed portions of said band for pivotally connecting them at their point of intersection, the crossed portion of said band comprising pieces of material underlying the inner member and overlying the outer member of said separable means, and fastening devices at both ends of said band adapted to detachably engage the top of the hose at predetermined spaced points.

2. A hose supporter composed of a continuous band adapted to surround the leg of a wearer with its end portions crossed, the crossed portions being comprised of two plies of material, a two-part separable fastening device for pivotally connecting the crossed portions of said band, one member of said device being secured to the outer ply of the underlying portion of the band and the other member being secured to the inner ply of the overlying portion of the band, and fastening devices adapted to detachably engage the top of the hose at predetermined spaced points.

3. A hose supporter composed of a continuous band adapted to surround the leg of a wearer with its end portions crossed, the crossed portions of said band being formed of two plies of material, a two-part fastening device for pivotally connecting the crossed portions of said band, one part of said device being secured to the inner ply of the overlying portion of the band, and fastening devices adapted to detachably engage the top of the hose at predetermined spaced point.

4. A hose supporter composed of a continuous band adapted to surround the leg of a wearer with its end portions crossed, said band comprising inelastic end portions and intermediate elastic portions, means secured to the crossed inelastic portions of said band for pivotally separably connecting them at their point of intersection, fastening devices at the ends of said band adapted to detachably engage the top of the hose at predetermined spaced points, and means for adjusting the length of said band.

5. In a garter, a leg-encircling band comprising a plurality of sections, each provided at one end with a member of a readily detachable connection whereby these ends of the sections may be disconnected for removing same, one of these sections being provided with adjusting means whereby the

length of the leg-encircling portion may be adjusted, the sections being crossed intermediate their ends and provided at their crossing point with a snap fastener whereby 5 they are pivotally and detachably connected.

6. A garter comprising a band adapted to surround the leg of the wearer and having its ends crossed, the crossed parts being pro-

vided at their point of intersection with a 10 separable pivotally connected snap fastener, the parts of which are covered to prevent contact thereof with the skin and clothing of the wearer.

In testimony whereof I have subscribed 15 my name.

HERMAN SACKS.
